United States Patent Office.

EDMUND L. COUNTISS, OF PHILADELPHIA, PENNSYLVANIA.

Letters Patent No. 62,940, dated March 19, 1867.

IMPROVED CAR-BRAKE SHOE.

The Schedule referred to in these Letters Patent and making part of the same.

TO ALL WHOM IT MAY CONCERN:

Be it known that I, EDMUND L. COUNTISS, of the city of Philadelphia, in the State of Pennsylvania, have invented a new and useful improvement on a Reversible Car-Brake Shoe; and I do hereby declare that the following is a full, clear, and exact description of the construction and operation of the same, reference being had to the annexed drawings, making a part of this specification, in which—

Figure 1 is a view of the shoe when set in its proper position.

Figure 2 is a vertical section of the same.

Figure 3 is a view of the shoe detached from the brake.

Figure 4 is a view of the receiver of the shoe with its sockets and slots.

Figure 5, a horizontal section of the socket of the receiver.

I construct the shoe of iron, in the ordinary shape, with catches *c c* at each end, with a square-headed lug, *d*, which enters the socket *g* of the receiver *b*. This receiver I construct of iron, in the shape shown, with the socket *g* in its centre. This socket is flanged to receive the lug *d*, and the bolt *e*, which fastens this receiver to the brake. I also provide the slot and hole at *l* for receiving the catch *e*. At the lower end of the receiver I construct a double-inclined slot or groove for the play of the catch *e* in reversing. When in place the shoe is retained by the catch *c* at the top, and the lug *d* in the centre. After the shoe has worn away at the top or upper part, it may be slipped out and reversed at once.

I do not claim the shape of the shoe, nor the reversible movement, as I am well aware that a reversible car-brake shoe has already been used which required pins or bolts to keep it in place; but what I claim as my invention, and desire to secure by Letters Patent, is—

The combination of the shoe, with the catches *c c* and the square-headed lug *d* attached, together with the receiver *b*, shaped as shown, with its slotted hole *l*, socket *g*, with its flanges, and the double-inclined groove, constructed and arranged in the manner described.

E. L. COUNTISS.
